US0D1097192S

(12) **United States Design Patent** (10) **Patent No.:** **US D1,097,192 S**
(45) **Date of Patent:** **** Oct. 7, 2025**

(54) **BIOMOLECULAR ANALYSIS DEVICE**

(71) Applicant: **Cytiva Sweden AB**, Uppsala (SE)

(72) Inventors: **Per Andreas Hakansson**, Uppsala (SE); **Michael Torn**, Uppsala (SE)

(73) Assignee: **Cytiva Sweden AB**, Uppsala (SE)

(**) Term: **15 Years**

(21) Appl. No.: **29/872,949**

(22) Filed: **Mar. 22, 2023**

(30) **Foreign Application Priority Data**

Oct. 12, 2022 (GB) 6236930

(51) LOC (15) Cl. 24-01

(52) U.S. Cl.

USPC **D24/216**

(58) **Field of Classification Search**

USPC D24/216, 232, 217, 231, 233, 185

(57) **CLAIM**

The ornamental design for a biomolecular analysis device, as shown and described.

DESCRIPTION

FIG. 1 is a back/left perspective view of a biomolecular analysis device;

FIG. 2 is a front/right view thereof; and,

FIG. 3 is a front/left view thereof.

1 Claim, 3 Drawing Sheets
